G. J. KLEIN.
LIGHTING FIXTURE.
FILED DEC. 17, 1920.

UNITED STATES PATENT OFFICE.

GEORGE J. KLEIN, OF CLEVELAND, OHIO.

LIGHTING FIXTURE.

Application filed December 17, 1920. Serial No. 431,454.

To all whom it may concern:

Be it known that I, GEORGE J. KLEIN, a citizen of the United States, residing at Cleveland, in the county of Cuyahoga and State of Ohio, have invented certain new and useful Improvements in Lighting Fixtures, of which the following is a specification.

My invention relates to improvements in lighting fixtures, and more particularly to that type or class known as "pendant" or "lantern" fixtures.

A further object is the provision of an improved lighting fixture adapted to be attached to or suspended from the ceilings of porches and other places exposed to the weather, and with this end in view the improved fixture is provided with an improved frame adapted to support, reinforce and protect the light diffusing shade or side walls, said shade or fixture frame being provided at its bottom with an open frame provided with a second similarly shaped frame hingedly connected at one side and carrying a light diffusing section said hinged frame being provided at its free side with a latching device for detachably connecting the hinged bottom section to the opposite or adjacent edge of the frame of the fixture.

The improved lamp body or shade, therefore, protects the source of illumination or lamp bulb and affords ready access to the same thru the light diffusing hinged bottom section.

With the above mentioned and other ends in view, the invention consists in the novel construction, arrangement and combination of parts, hereinafter described, illustrated in some of its embodiments in the accompanying drawings and particularly pointed out in the appended claim.

Referring to the drawings, forming a part of this specification, Figure 1 is a perspective view of a lighting fixture of the pendant ceiling type constructed in accordance with this invention, the hinged connected bottom section for inserting and removing a light or lamp bulb being shown in open position.

Fig. 2, a similar view of a lighting fixture of the pendant or lantern type showing a modified form of hinged bottom section.

Similar numerals of reference designate like parts thruout all the figures of the drawings.

The improved lighting fixture comprises a suitable rectangular top frame 1, and as a means of adapting the improved fixture for use as a pendant ceiling fixture the top frame 1, is preferably made in the form of a rectangular attaching flange as shown in Fig. 1 of the drawings, and provided with an opening adapted to receive the light or lamp bulb 2, and also to receive and support the top of the pendant fixture frame hereinafter described.

The attaching flange 1, may be provided with openings adapted to receive and contain attaching elements or screws 3, to enter the overhanging or ceiling wall 4.

In the form shown in Fig. 2, the overhanging top frame 1, may be provided with a closed top or covering 5, and may be suspended from any suitable and convenient pendant or suspensory device.

As a means of protecting, supporting and reinforcing the light diffusing shade or side walls 6, and particularly protecting the corners of the latter, an improved pendant frame is provided, said frame consisting of pendant angle corner members 7, arranged within and connected to the inner corner portions of the rectangular top frame 1, and terminating at the bottom in a relatively fixed open bottom frame 8.

As a means of protecting the light source or bulb 2, as well as providing means for inserting or removing such lamp bulb without disturbing the main body portion of the fixture, a second bottom frame 9, is provided, said frame being similar in shape to the open bottom frame 8, and being adapted to close the same, said bottom frame 9, being provided with a light diffusing wall or section 9^a.

As a convenient means of attaching the second bottom frame 9, to the frame 8, of the fixture, one side of the frame 9, is provided with hinge members 9^b, secured to one side of the bottom frame 8, the opposite or free edge of the bottom frame 9, being provided with a latching device consisting, in the present instance, of a pivotally mounted hook shaped latch member 9^c, adapted to enter a loop or staple member 9^d, attached to the adjacent portion of the fixed bottom frame 8, the free edge of the frame 9, being provided with a slot 9^e, thru which the eye portion of the staple 9^d, is adapted to enter.

If desired, the second or bottom frame 9', may be provided with depending frame 110

members 9^a, adapted to support a plurality of shade members 9^b, as shown most clearly in Fig. 2 of the drawings.

In the form shown in Fig. 1, the light diffusing or shade walls 6, are further protected and reinforced by means of intermediate frame members 7^a, and vertically extending intermediate metallic strips 7^b.

Having thus described some of the embodiments of my invention, what I claim and desire to secure by Letters Patent, is,—

In a lighting fixture, a rectangular top frame having inner corner portions, pendant angle corner members seated within and connected to said inner corner portions of

said top frame, a relatively fixed rectangular bottom frame having corners seated in and covered by the lower ends of said pendant angle corner members, a relatively movable bottom frame hinged to one side of said relatively fixed rectangular bottom frame and detachably connected to the other side thereof, and a light diffusing section carried by said bottom frame and having its edges spaced within 25 and protected by the marginal edges of said bottom frame.

In testimony whereof I have affixed my signature.

GEORGE J. KLEIN.
